INSTRUMENT CASING

Joseph L. Laub and Will Timm, Altadena, and Paul L. Huey, Whittier, Calif.

Application March 13, 1958, Serial No. 50,021

Term of patent 14 years

(Cl. D26—5)

FIG. 1.

FIG. 2.

FIG. 3.

FIG. 4.

FIG. 5.

FIG. 6.

Figure 1 is a front perspective view of an instrument casing showing our new design;

Figure 2 is a front elevational view thereof;

Figure 3 is a rear elevational view thereof;

Figure 4 is an elevational side view thereof, the other side being a mirror image;

Figure 5 is a top view thereof; and,

Figure 6 is a bottom view thereof.

The broken line showings of representative control knobs and switches on the front panel of the casing are for illustrative purposes only.

We claim:

The ornamental design for an instrument casing, as shown and described.
